UNITED STATES PATENT OFFICE

JERIE EVICH, OF SANTA BARBARA, CALIFORNIA

DESIGN FOR AN AUTOMOBILE SIGNAL LAMP

Application filed March 9, 1932. Serial No. 43,136. Term of patent 14 years.

To all whom it may concern:

Be it known that I, JERIE EVICH, a citizen of the United States, residing at Santa Barbara, in the county of Santa Barbara and State of California, have invented a new, original, and ornamental Design for Automobile Signal Lamps, of which the following is a specification, reference being had to the accompanying drawing, forming part thereof.

Figure 1 is a perspective view showing my new design; both ends of the article are of substantially identical appearance.

Figure 2 is an end elevation of the lamp shown in Figure 1.

I claim:

The ornamental design for an automobile signal lamp substantially as shown and described.

JERIE EVICH.
